PLUMBING MANIFOLD

Alfred W. Allen, Greensboro, N. C.

Application January 4, 1951, Serial No. 204,426

Claims.

This invention relates to a plumbing fixture and more particularly to a manifold constituting a single fixture to which may be connected the supply pipes to and from the bathtub and lavatory, and the drains from these fixtures, as well as a common drain to the soil stack and a water connection to the flush tank. A device of this nature is useful and advantageous in the simplification of piping layouts in residence plumbing, providing a single point which may be conveniently located with respect to all of the fixtures, to which all of the pipe connections from said fixtures may be brought. It is of inestimable value in "roughing in" the plumbing for bathrooms which are to be equipped later, in which the precise location of the fixtures is not yet ascertained, by providing a focal point to which the various fixtures may later be connected.

One of the objects of the invention is to provide a plumbing manifold that can be set upon the floor, between joists, or in any other desired location, and serve as a common meeting place for the hot and cold water supply pipes from the service line and water heater and the water connections to the bathtub, lavatory and flush tank, as well as the drains from the bathtub and lavatory to the manifold and from the manifold to the soil stack.

Another object of the invention is to provide a manifold for the purpose described, which may be fabricated in sections, comprising an extruded section of uniform cross-sectional shape which includes the longitudinal passages, and one or more cast fittings integrated with the extruded portion, said cast fittings including those branch passages which extend angularly from the longitudinal passages and open to the exterior of the manifold.

Still another object of the invention is the provision of a manifold as described which can be made in any length to suit particular conditions, by reason of the uniform cross-sectional shape of the extruded portion thereof which can be cut to any length.

A further object of the invention is to provide a manifold incorporating means for sealing the joints between the several passage connections, in the sectional version of the device.

Still another object of the invention relates to means aside from the pipe connections for securing the manifold in fixed position, this being especially useful when making sweated connections with the manifold.

Other objects of the invention will appear as the following description of a preferred and practical embodiment thereof proceeds.

(CL 4-191)

2

In the drawing throughout the several figures of which the same reference characters have been used to denote identical parts:

Figure 1 is a side elevation partly in section of a plumbing manifold embodying the concept of my invention;

Figure 2 is a plan view partly in section:

Figure 3 is a view in vertical section, taken along the line 3—3 of Figure 2;

Figure 4 is a cross-section taken along the line 4—4 of Figure 3;

Figure 6 is a cross-section taken along the line

Figure 7 is a section taken along the line 7-7.

20 Referring now in detail to the several figures, the numeral 1 represents an embodiment of the manifold of my invention as a whole, which consists of a metal body 1', having three parallel longitudinal passages 2, 3 and 4 extending substantially therethrough, opening in the face of
25 the manifold at the left end, as indicated in Figures 1 and 2. At the opposite end of the manifold the said longitudinal passages have upturned ends 5, 6 and 7 forming elbows in the manifold, which open in the top face thereof.

30 The passages 2 and 3 are of relatively small diameter and form water conduits. The large diameter passage 4 is a drain. Adjacent their middle, the small diameter passages communicate with downwardly extending branches 8 and 9, and the drain passage 4 has a downwardly extending branch 10. The branches 8, 9 and 10 open in the lower face of the manifold. The ends of all the passages which open in the face of the manifold may be threaded for iron pipe, or left unthreaded for sweated joints when copper pipe is used. Threaded connections are indicated in the drawing.

The downward branches 8 and 9 are designed to be connected respectively to the cold and hot water supply pipes 11 and 12, and the branch 10, to a pipe 13 which discharges into the soil stack. The lefthand ends of the passages 2, 3 and 4 are intended to be connected respectively to the cold and hot bathtub fixtures and to the bathtub drain.

50 drain. The upper ends 5, 6 and 7 of the passages 2, 3 and 4 are for connection with the hot and cold fixtures of the lavatory and with the lavatory drain, the latter being seen at 14.

55 The cold water passage 2 has an upwardly extending branch passage 14' adjacent its middle.

connected by the pipe 15 with the flush tank. The drain passage 4 has an upwardly extending branch 16 closed by a deck plate 17, having two depressions 18 for an unscrewing tool. This branch is to give access to the drain passage for unstopping it when clogged.

It is obvious from the above detailed description that I have provided a manifold forming a focal point to which come the hot and cold water supply to the bathroom, from which point it is distributed to the several fixtures, and to which point the drainage from the supplied fixtures returns, excepting of course, the discharge flow from the flush tank.

The plumbing manifold 1 may be an integral casting, if desired, but in the illustrated embodiment of the invention it is a fabricated structure made up of one or more sections 19, containing the parallel longitudinal tubular passages, integrated with intermediate and/or end sections containing the T and elbow diversions. Since the sections 19 are of uniform cross-section, they may be extruded in stock length units which are cut to the size required for the particular manifold being made up. The elbow and T sections are cast.

The intermediate section 20 has flat identical end faces 21, one of which is shown in Figure 5. This section includes intermediate parts of the passages 2, 3 and 4. The flat faces 21 are surrounded by shallow peripheral flanges 22, which are beveled on the inside as indicated at 23 in Figure 3, and the extruded sections 19 after having been cut from a stock length are correspondingly beveled at the end as at 24 in Figure 5, with a file or other tool, to fit within the flange 22 against the beveled side thereof. A narrow space is defined between the adjacent end faces of the section 20 and the extruded section forming a cell for solder.

In connecting the intermediate section 20 to the extruded section 19, the thin walled thimbles 25 are employed, which fit snugly the respective passages, each having a feather-edged circumferential collar 26 about its middle. A thin gasket 27 of solder is used, having a hole pattern corresponding to the passage arrangement in the sections to be joined. This gasket is placed within the recess bounded by the flange 22 of the intermediate section. Then the thimbles are pushed through the holes in the gasket and into the portions of the passages 2, 3 and 4 in the intermediate section. Then the extruded section is pushed over the projecting parts of the thimbles. The joint is subjected to endwise pressure while a blowtorch or other heating means is applied. As the solder melts it is forced through the entire interface between the sections, including the juncture formed by the baffles 23 and 24, making a thorough sweated joint between said sections. The thimbles keep the solder from leaking into the passages which the joint intersects.

When, as in Figure 1, the section 20 is between two extruded sections, the details of the joint on each side of the intermediate section are identical.

The same procedure is followed with respect to an end section, such as the section 28, which is shown in Figures 1, 2, 6 and 7. The end section is provided with a flat end face 29, bounded by the peripheral tapered flange 30; the extruded section 19 is correspondingly chamfered at the adjacent end; the two sections are juxtaposed with thimbles 25 connecting the aligned parts of the passages, and a gasket 27 of solder placed in

the joint. The joint is completed by heating the parts, pressing them together while the solder is molten.

The plumbing manifold of the present invention is preferably located below floor level, but is capable of being placed anywhere that may be most convenient. It is here shown as being mounted upon a board 31, presumably secured sufficiently low between joists so that the level of the subfloor upon which the tile are laid comes to the line a—a in Figure 4. The cast sections are provided with elevated faces or tables 32 and 33, which are flush with top surface of the tile and may be suitably enameled for appearance, if the manifold is not of corrosion resisting material. The deck plate 17 is flush with the tile.

Mainly to save weight and material, the extruded sections 19 are hollowed out underneath, as indicated at 34, Figures 4 and 5, the hollow defining side flanges 35 and 36 formed with interior longitudinal shoulders 37. Fasteners 38, having resilient arms 39 and 40, are screwed to the board 31, the arms being shaped to snap over the shoulders when the manifold is pressed down upon the fasteners, thereby holding the manifold in place. This is of importance in preliminarily locating the manifold while the pipe connections are being measured for length, and it is particularly important in holding the manifold immobile when making sweated joints with it.

While I have in the above description disclosed what I believe to be a preferred and practical embodiment of the invention, it will be understood by those skilled in the art that the specific details of construction and arrangement of parts, as shown and described, are by way of example and not to be construed as limiting the scope of the invention.

What I claim is:

1. Plumbing manifold comprising a unitary elongated body of generally rectangular cross-section having a plurality of parallel passages therethrough opening in one end of said body and in the top of said body adjacent the opposite end, the axes of said passages at their opposite ends being perpendicular, two of said passages being relatively small, to serve as conduits for water under pressure, the other being relatively large to serve as a drain, said body being formed with branch passages communicating with said first named passages at an intermediate point in the length of said first named passages and perpendicular thereto.

2. Plumbing manifold comprising a unitary elongated body of generally rectangular cross-section having a flat face at one end and flat top faces respectively at an intermediate point and adjacent the opposite end, said flat top faces being elevated above the general level of the top of said manifold and being at the same level, a plurality of parallel passages extending through said manifold, opening in said flat end face and the flat top face which lies adjacent the opposite end, the axes of said passages at opposite ends being perpendicular, two of said passages being relatively small to serve as conduits for water under pressure, the other being relatively large to serve as a drain, said body having downwardly extending branch passages communicating respectively with said first named passages in the zone overlain by said intermediate flat top face, the latter having an access passage communicating with said relatively large passage, and a closure for said access passage.

3. Plumbing manifold as claimed in claim 2, the bottom of said body being recessed to form longitudinal side flanges having interior longitudinal shoulders, and securing means for said manifold including resilient clips adapted to be anchored to a support and having resilient arms with cam bulges adapted to enter said recessed bottom and snap over said shoulders.

4. Fabricated plumbing manifold comprising a section of substantially uniform cross-section having a plurality of rectilinear parallel passages therethrough, two of said passages being relatively small to serve as conduits for water under pressure, another being relatively large to serve as a drain, and a section including extensions of said passages and branches thereof perpendicular thereto, said sections having adjacent flat end faces in juxtaposition slightly spaced to form a solder cell, one of said faces having a bounding flange bearing against a complementary chamfered edge about the other of said faces, thimbles fitting the registering ends of said passages and extensions, intersecting the joint between said faces and a solder gasket between said faces for uniting said sections.

5. Fabricated plumbing manifold comprising a section of substantially uniform cross-section having a plurality of rectilinear parallel passages therethrough, two of said passages being relatively small to serve as conduits for water under pressure, one being relatively large to serve as a drain, and a section including rectilinear extensions of said passages and upwardly directed branches thereof perpendicular thereto, said second named section having a flat top face in which said branches open, said sections having adjacent flat end faces in juxtaposition slightly spaced to form a solder cell, one of said faces having a bounding flange bearing against a complementary chamfered edge about the other of said faces, thimbles fitting the registering ends of said passages and extensions, intersecting the joint between said faces and a solder gasket between said faces for uniting said sections.

6. Fabricated plumbing manifold comprising lateral sections of substantially uniform cross-section, and an intermediate section, said sections being in end abutment and having a plurality of rectilinear parallel passages extending continuously therethrough, opening in the opposite ends of said lateral sections, two of said passages being relatively small to serve as conduits for water under pressure, one being relatively

large to serve as a drain, said intermediate section having branches of said passages perpendicular thereto opening in the bottom face of said intermediate section, and having an upwardly extending branch from one of said relatively small passages and an upwardly extending access branch from said relatively large passage, a closure for said access branch, said sections having adjacent flat end faces in juxtaposition slightly spaced to form a solder cell, one of said faces having a bounding flange bearing against a complementary chamfered edge about the other of said faces, thimbles fitting the registering ends of said passages and extensions, intersecting the joint between said faces and a solder gasket between said faces for uniting said sections.

7. Fabricated plumbing manifold comprising lateral sections of substantially uniform cross-section, an intermediate section and an end section, said sections being in similar end-to-end abutment and having a plurality of rectilinear parallel passages extending continuously therethrough opening in one end of said manifold and adjacent the opposite end of said manifold in the top face of said end section, two of said passages being relatively small to serve as conduits for water under pressure, one being relatively large to serve as a drain, said intermediate section having branches of said passage perpendicular thereto opening in the bottom face of said intermediate section, and having an upwardly extending branch from one of the relatively small passages and an upwardly extending access branch from said relatively large passage, a closure for said access branch, the abutting faces of the sections of said series having a bounding flange on one bearing against a chamfered edge about the other, the bounded faces being flat and slightly spaced to form a solder seal, said parallel passages opening in said faces, thimbles fitting the registering ends of said passages, intersecting the joint between said faces, and a solder gasket between said faces for uniting adjacent sections.
